UNITED STATES PATENT OFFICE.

JAMES A. GRAY, OF SAN FRANCISCO, CALIFORNIA, ASSIGNOR TO AMERICAN CAN COMPANY, OF SAN FRANCISCO, CALIFORNIA, A CORPORATION OF NEW JERSEY.

APPARATUS FOR INTERLOCKING AND UNITING THE HOOKED EDGES OF BLANKS TO FORM CAN BODIES.

Application filed November 12, 1924, Serial No. 749,497. Renewed March 26, 1928.

The present invention relates to the class of can body forming apparatus.

The object of my invention is to provide a machine for automatically assembling a can body from two pre-formed blanks, by inter-locking the meeting edges of said blanks in the form of mechanically rigid seams which can be subsequently soldered or otherwise treated to make a permanent and tight can body. The use of a machine embodying my present invention results in a great saving of both time and labor over the usual method of first assembling the blanks by hand and then uniting their interfitting edges in a bumping press. Its use also results in a more uniform product, the percentage of imperfect seams in machine assembled can bodies being much less than in those initially assembled by hand.

A further object of the invention is to provide a continuously operating machine requiring no further attention than the feeding of the blanks and the removal of the formed can bodies. Other objects and advantages of the invention will become apparent from the following specification wherein a preferred embodiment of the said invention is fully described. It is to be understood, however, that the form and construction of the machine herein described and illustrated may be varied, within the limits of the claims hereto appended, without departing from the spirit of the invention as expressed in said claims.

With this in view my invention will now be fully described with reference to the accompanying drawings, wherein:

Fig. 1 is a side elevation of my complete machine.

Fig. 2 is a part sectional front end elevation of the same, as viewed from the right of Fig. 1.

Fig. 3 is a plan view, enlarged, of the feed hopper, the upper portion of the horn, the lateral guides, and the blank-advancing feed slides.

Fig. 4 is a part sectional side elevation, enlarged, of the feed hopper, the horn, the bumping members, and one of the lateral guides.

Fig. 5 is a transverse section of the feed hopper, taken in the direction of the arrows on the lines 5—5 of Figs. 1, 3 and 4.

Fig. 6 is a detailed plan view of a portion of the feed slides. 55

Fig. 7 is a sectional detail of the clamping means, taken in the direction of the arrows on the line 7—7 of Fig. 1.

Figs. 8, 9 and 10 are broken transverse sectional details, enlarged, taken in the direction of the arrows on the respective lines 8—8, 9—9, and 10—10 of Figs. 1, 3 and 4, and showing the successive steps in the formation of the seams or joints between the edges of the blanks. 60

Fig. 11 is a sectional detail of one of the bumping members taken in the direction of the arrows on the line 11—11 of Fig. 2.

Fig. 12 is a sectional detail, enlarged, of one of the stop guides, taken in the direction 70 of the arrows on the line 12—12 of Fig. 2.

The machine herein illustrated and described is designed for the formation of can bodies of square cross section, such for example, as those used in the manufacture of 75 the familiar five-gallon cans. However, by obvious changes in the size and relative positions of its several parts, the machine may be used with equal success for forming can bodies of other shapes or sizes. 80

In the drawings, the reference numeral 13 designates a base, from the rear end of which rises an upright frame structure 14, Fig. 1, supporting a hopper 15 adapted for receiving the can body blanks. Said blanks, as 85 shown at 16 in Fig. 5, are of the usual form employed in the manufacture of can bodies of the type described, each blank being bent along its center line to form two sides of the can body, and the side edges of the two 90 blanks being oppositely flanged, as shown at 17, to form hooks capable of interengagement. The bottom of the hopper 15 is V-shaped, as shown, and it is provided with a central vertical partition 18, the two blanks 95 16 being placed on opposite sides of said partition in the positions illustrated.

The partition 18 is extended forwardly in the form of a horn 19, Figs. 1, 2, 3, and 4, provided with upper and lower enlarged 100

- heads or faces 19'. Said horn is provided with lateral bosses 20, Figs. 2, 3 and 4, in which are mounted guide rails 21 adapted to guide the advancing blanks by engagement with their interior central angles, as shown in Fig. 5. Immediately outside the guide rails 21 are reciprocating feed slides 22, extending the entire length of the machine, and provided with spaced inwardly projecting spring actuated dogs 23, as shown in Fig. 6. The length of the stroke of said feed slides and the spacing of said dogs are so proportioned that each dog, or more properly each pair of oppositely disposed dogs, engage the rear ends of a pair of blanks and move the same forwardly at each forward movement of said feed slides. Thus there are a series of pairs of blanks in the machine at all times, as indicated in dotted lines in Fig. 3, the entire series being moved forwardly, at each forward stroke of the feed slides 22, by a distance slightly greater than the length of one blank. The guide rails 21 are provided with grooves 24, Figs. 3, 4, and 5, in which the dogs 23 operate to enable them to engage the rear ends of the blanks 16.
- The feed slides 22 are mounted in suitable guides 25, Figs. 2 and 5, at the ends 30 of the machine, and are reciprocated by levers 26, Figs. 1 and 2, secured to a shaft 27 and connected with said slides by links 28. The shaft 27 is oscillated by a lever 29 which is connected by a rod 30 with a crank 31 secured upon a continuously rotating shaft 32 journaled in an upright frame or yoke 33 at the forward end of the machine.
- The hopper 15 is provided, at its forward 40 end, with inclined upper guide plates 34, Figs. 1, 4 and 5, which initially guide the blanks onto the horn 19 and the lateral guide rails 21. Said horn, immediately forward of the hopper 15, has its heads 19' formed as shown in cross section in Fig. 8, with under-cut depressed portions 35 and raised portions 36. Correspondingly shaped fixed guide plates 37 and 38 are positioned in close spaced relation to said horn portions or surfaces 35 and 36, so that the blanks 16, in passing between the horn and said guide plates 37 and 38, are brought into position to enable their hooked or flanged edges 17 to engage each other, such engagement being brought about by the gradual flattening out of the horn surfaces as shown in Fig. 3, the guide plates 37 and 38 being also brought together to conform to the changing contour of the horn.
- When the mutually engaged blanks are advanced through another step of their forward movement, they pass between the horn and spring actuated pressing members 39, Figs. 1 and 9, which initially or par-
- tially clinch the inter-engaged flanges 17. 65 The portion of the horn under-lying said pressing members is provided with smooth surfaces, as shown at 40 in Figs. 3, 4 and 9, and said pressing members are formed to correspond thereto, as shown in Figs. 1 70 and 9. Said members are carried upon pins 41 which are vertically movable in fixed supports 42, and springs 43 press them against the horn surfaces 40. The rear ends of said members are inclined upwardly, as 75 shown at 44 in Fig. 1, to permit the blanks to enter between them and said horn surfaces.
- The next succeeding movement of the blanks 16 brings them to their endmost or 80 last position at the forward end of the horn, and during their period of rest in this position the partially clinched inter-engaged flanges 17 are firmly and finally clinched by a bumping process which will now be 85 described. The frame yoke 33 carries an upper horizontal shaft 45, Figs. 1 and 2, spaced above and parallel to the shaft 32. Both said shafts are provided with gears 46, which are driven by a common pinion 47 90 connected with a belt pulley 48. Said shafts are also provided with cranks or eccentrics 49, Figs. 1, 2, and 11, journaled in trunnion blocks 50 operating in rectangular sockets in the shanks 51 of the bumping 95 hammers, said shanks being suitably mounted for vertical reciprocating movement in fixed guides 52. The heads 53 of said bumping hammers are elongated in the direction of the length of the horn, and 100 are formed as shown in Fig. 10 to cooperate with said horn to finally clinch and flatten the seam formed by the inter-engaged flanges 17 of the blanks 16. The heads 19' of the horn are provided at this point with 105 longitudinal grooves 54, Figs. 3 and 10, adapted to receive said seam. The blanks 16 are moved to their fixed position, of course, while the bumping hammers 53 are separated from the horn heads 19', and then, 110 during the period of rest of said blanks, said hammers are forced against said horn with the necessary pressure to finally clinch and flatten the seam. Said hammers then 115 separate again, and the next forward movement of the feed slides 22 pushes the assembled can body out of the machine.
- The two blanks 16 are properly aligned with each other, endwise, by stop members 55, Figs. 2 and 12, pivotally mounted upon fixed pivots 56, and frictionally connected with the hammers 53. These connections are formed by pins 57 fixed in the end faces of said hammers and extending through radial slots in the stops 55, and springs 58 120 for pressing said stops against the ends of said hammers. Adjusting screws 59, carried in fixed brackets 60, limit the outward

movement of the stops 55, and their inward movement is limited by contact with the horn 19. Thus, upon the separation of the hammers 53, the stops 55 are moved against 5 their limiting screws 59, as shown in Figs. 2 and 11, in which position the spaces between said stops and the horn surfaces are sufficient to permit the finally clinched and flattened flanges 17 of the united blanks 16 to pass through, but said spaces are not sufficient to permit the passage of the partially clinched flanges of the next succeeding pair of blanks. Thus the partially united blanks are mutually aligned, endwise, upon 15 being moved into position between the hammers 53, by the abutment of the ends of their flanges 17 against the stops 55.

After the partially united blanks have been moved into position between the bumping hammers 53, they are clamped, to hold 20 them securely in such position during the bumping operation. For this purpose there are provided pivotally mounted gripping members or jaws 61, Figs. 1 and 7, adapted 25 to clamp the blanks, at their rear ends, against the horn 19. Said jaws are operated by oscillating rods 62 which carry arms 63 at their outer ends, and said arms are provided with rollers 64 adapted to follow 30 cams 65 formed upon the inner flanges of the gears 46. Springs 66 return said jaws to their normal or free positions. The cams 65 are so positioned angularly with respect to the bumping cranks 49 that the jaws 61 35 are caused to clamp the rear ends of the blanks as soon as the feed bars 22 come to rest, and to release said blanks at or before the conclusion of the bumping operation. The swinging movement of said jaws 61 in 40 clamping the blanks causes said blanks to be shoved forwardly firmly against the stops 55 to insure their mutual endwise alignment.

In order to insure that the partially 45 clinched flanges 17 of the blanks 16 will be fully seated within each other prior to the final clinching or bumping process, the lateral guide rails 21 are slightly enlarged, as shown at 67 in Fig. 3, at their forward end 50 regions. This causes the blanks, when moved to their final position between the bumping hammers, to be slightly spread apart, thereby placing the joints formed by the inter-engaging hooked flanges under 55 strain to insure that said flanges will be fully and firmly seated within each other.

The machine herein set forth is or may be used as one of the instrumentalities for the performance of my method of making angular containers, set forth in my application 60 Serial No. 142,832, filed October 20, 1926, in which my said method is claimed.

I claim:

1. A machine for the described purpose 65 comprising means for receiving a pair of

separate blanks having hooked flanges capable of mutual inter-engagement, a horn having means for causing the inter-engagement of said flanges, means for feeding the sheets along the horn so as to be inter-engaged by their hooked flanges, and means for clinching the inter-engaged flanges to unite the two blanks. 70

2. A machine for the described purpose comprising a holder for receiving a pair of 75 separate blanks having flanges capable of mutual inter-engagement, a horn having means for causing the inter-engagement of said flanges as the sheets are fed along the horn, means for clinching the inter-engaged 80 flanges to unite the two blanks, and means for moving said blanks from the holder to the inter-engaging means and thence to the clinching means.

3. A machine for the described purpose 85 comprising means for receiving a pair of separate blanks having flanges capable of mutual inter-engagement, said receiving means having confining and guiding devices for engaging said blanks when bent 90 into angular form, and means operating while the blanks are moving for causing the inter-engagement of said flanges to unite said blanks, and means for so moving the blanks. 95

4. A machine for the described purpose comprising means for receiving a pair of 100 separate blanks having flanges capable of mutual inter-engagement, means for advancing said blanks in the direction of the length of said flanges, and means against which the blanks are moved for causing the inter-engagement of said flanges during and by the aid of the advancing movement of said blanks. 105

5. A machine for the described purpose comprising means for receiving a pair of 110 separate blanks having flanges capable of mutual inter-engagement, means for advancing said blanks in the direction of the length of said flanges, means which are fixed and against which the blanks are advanced for causing the inter-engagement of said flanges during the advancing movement of the blanks, and means for clinching the 115 inter-engaged flanges to unite said blanks.

6. A machine for the described purpose comprising means for receiving and separately holding a pair of separate blanks having flanges capable of mutual inter-engagement, means for advancing said blanks in the direction of the length of said flanges, and means for simultaneously moving said blanks transversely inwardly and then outwardly to effect the inter-engagement of 120 said flanges. 125

7. A machine for the described purpose comprising means for receiving a pair of 130 separate blanks having flanges capable of mutual inter-engagement, means for ad-

vancing said blanks in the direction of the length of said flanges, and guide members against which the blanks are forced edge-wise and adapted to engage and deflect 5 said flanges during the advancing movement of said blanks to effect the inter-engagement of said flanges.

8. A machine for the described purpose comprising a holder for receiving and separately holding a pair of separate blanks 10 having flanges capable of mutual inter-engagement, said receiving means having confining and guiding devices for engaging said blanks when bent into angular form, 15 means for clinching said flanges together to unite the blanks, and means for moving said blanks from said holder to said clinching means.

9. A machine for the described purpose comprising a holder for receiving within it 20 a pair of separate angle blanks having flanges capable of mutual inter-engagement, a horn extending from said holder, a bumping member for clinching said flanges together to unite the blanks, and means for moving said blanks from said holder and along the horn and into the sphere of action of said bumping member.

10. A machine for the described purpose comprising a holder for receiving a pair of 30 separate blanks having flanges capable of mutual inter-engagement, said holder engaging the outer sides of the blanks and having means for holding said blanks separated, 35 oppositely reciprocating bumping members for clinching said flanges together to unite the blanks, and means for moving said blanks from said holder into the sphere of action of said bumping members.

40 11. A machine for the described purpose comprising a holder for receiving a pair of separate blanks having flanges capable of mutual inter-engagement, said holder engaging the outer sides of the blanks and having 45 means for holding said blanks separated, means for clinching said flanges together to unite the blanks, and means for feeding said blanks from said holder to said clinching means and for discharging the united blanks 50 therefrom.

55 12. A machine for the described purpose comprising a holder for receiving a pair of separate blanks having flanges capable of mutual inter-engagement, said holder engaging the outer sides of said blanks and having 60 means for holding said blanks separated, a horn extending from said holder and having means for clinching said flanges together to unite the blanks, and a reciprocating member for moving said blanks from said holder to said clinching means.

65 13. A machine for the described purpose comprising a holder for receiving a pair of separate blanks having flanges capable of mutual inter-engagement, said holder engag-

ing the outer sides of said blanks and having means for holding said blanks separated, a horn extending from said holder and having means for clinching said flanges together to unite the blanks, and a pair of reciprocating feed slides for moving said blanks from said holder to said clinching means. 70

14. A machine for the described purpose comprising a holder for receiving a pair of blanks having flanges capable of mutual inter-engagement, a horn extending from said holder and having fixed means for effecting the inter-engagement of said flanges, means for partially clinching the inter-engaged flanges, and means for finally clinching said flanges together to unite said blanks. 75

15. A machine for the described purpose comprising a holder for receiving a pair of blanks having flanges capable of mutual inter-engagement, a horn extending from said holder and having fixed means for effecting the inter-engagement of said flanges, means for partially clinching the inter-engaged flanges, and a bumping member for finally clinching said flanges together to unite said blanks. 80

16. A machine for the described purpose comprising a holder for receiving a pair of blanks having flanges capable of mutual inter-engagement, a horn extending from said holder and having fixed means for effecting the inter-engagement of said flanges, means for partially clinching the inter-engaged flanges, means for finally clinching said flanges together to unite the blanks, and means for moving said blanks from said holder and successively through the respective spheres of action of said inter-engaging and clinching means. 85

17. A machine for the described purpose comprising a holder for receiving a pair of blanks having flanges capable of mutual inter-engagement, means for effecting the inter-engagement of said flanges, means for partially clinching the inter-engaged flanges, means for finally clinching said flanges together to unite the blanks, and means for advancing said blanks, by a series of successive step movements, from said holder through the respective spheres of action of said inter-engaging and clinching means. 110

18. A machine for the described purpose comprising a holder for receiving a pair of separate blanks having flanges capable of mutual inter-engagement, means for advancing said blanks from said holder by a series of successive step movements alternating with periods of rest, means for effecting the inter-engagement of said flanges during one of said movements, means for partially clinching the inter-engaged flanges during a succeeding movement, and means for finally clinching said flanges together during a succeeding period of rest. 115

19. The combination of a horn, a partition at the rear end of said horn, means for enclosing a can body blank formed with hooked edges at each side of said partition, means for feeding said blanks on to and along said horn, means for causing the hooked edges of one blank to interlock with the hooked edges of the other blank as the blanks are fed along the horn, and means for clinching together said hooked edges to form said blanks into a can body.
20. A machine for the described purpose comprising means for receiving and advancing a pair of separate blanks having flanges capable of mutual inter-engagement, fixed means for deflecting and effecting the inter-engagement of said flanges during the advancing movement of said blanks, means for advancing said blanks against and along said deflecting means, and means for clinching the inter-engaged flanges together to unite said blanks.
21. A machine for the described purpose comprising means for receiving and advancing a pair of separate blanks having flanges capable of mutual inter-engagement, means for effecting the inter-engagement of said flanges during the advancing movement of said blanks, means for partially clinching the inter-engaged flanges during said advancing movement, and separate means for finally clinching said flanges together to unite said blanks.
22. A machine for the described purpose comprising means for imparting forward movement, followed by a period of rest, to a pair of separate blanks having flanges capable of mutual inter-engagement, fixed means for deflecting and effecting the inter-engagement of said flanges during said movement, and means for clinching the inter-engaged flanges together, to unite said blanks, during said period of rest.
23. A machine for the described purpose comprising means for imparting forward movement, followed by a period of rest, to a pair of separate blanks having flanges capable of mutual inter-engagement, means for effecting the inter-engagement of said flanges during said movement, means for partially clinching the inter-engaged flanges during said forward movement, and means for finally clinching said flanges together, to unite said blanks, during said period of rest.
24. In a machine for uniting the inter-fitting flanges of can body blanks, means for initially and partially clinching the inter-fitting flanges, and separate means for finally clinching the partially clinched flanges.
25. In a machine for uniting the inter-fitting flanges of can body blanks, a spring actuated pressing member for initially and partially clinching the inter-fitting flanges, and means for clamping the blanks to hold said flanges in
- and separate means for finally clinching the partially clinched flanges.
26. In a machine for uniting the inter-fitting flanges of can body blanks, a spring actuated pressing member for initially and partially clinching the inter-fitting flanges, and a reciprocating bumping member for finally clinching the partially clinched flanges.
27. In a machine for uniting the inter-fitting flanges of can body blanks, means for imparting forward movement, followed by a period of rest, to the blanks, means for partially clinching the inter-fitting flanges during said forward movement, and means for finally clinching the partially clinched flanges during said period of rest.
28. In a machine for uniting complementary flanges of can body blanks, means for effecting the inter-engagement of the complementary flanges, means for initially and partially clinching the inter-engaged flanges, and separate means for finally clinching the partially clinched flanges.
29. In a machine for uniting complementary flanges of can body blanks, means for imparting forward movement, followed by a period of rest, to the blank, means for effecting the inter-engagement and the partial clinching of the complementary flanges during said forward movement, and means for finally clinching the partially clinched flanges during said period of rest.
30. In a machine for uniting complementary flanges of can body blanks, means for effecting the inter-engagement of the complementary flanges, and a spring actuated member for partially clinching the inter-engaged flanges.
31. In a machine for uniting the inter-fitting flanges of can body blanks, a spring actuated member for partially clinching the inter-fitting flanges, and means for moving said flanges through the sphere of action of said member.
32. In a machine for uniting the inter-fitting flanges of can body blanks, a pair of pressing members, resilient means for holding said members together, and means for moving the inter-fitting flanges between said members to partially clinch the same.
33. In a machine for uniting complementary flanges of can body blanks, a horn, guide members associated with said horn for effecting the inter-engagement of said flanges, a pressing member associated with said horn for partially clinching the inter-engaged flanges, a bumping member associated with said horn for finally clinching said flanges, and means for moving the blanks along said horn to carry said flanges through the spheres of action of said members.
34. In a machine for uniting the inter-fitting flanges of can body blanks, means for clamping the blanks to hold said flanges in

inter-fitting relation, and means for clinching together the flanges of the clamped blanks.

35. In a machine for uniting the inter-fitting flanges of can body blanks, means for aligning the inter-fitting flanges endwise, means for clamping the blanks to hold said flanges in inter-fitting aligned relation, and means for clinching together the flanges of the clamped blanks.

36. In a machine for uniting the inter-fitting flanges of can body blanks, a stop member, means for moving the ends of the inter-fitting flanges against said stop mem-

ber to align with same, and means for clinching the aligned inter-fitting flanges together.

37. In a machine for uniting the inter-fitting flanges of can body blanks, a stop member, a gripping member for moving the ends of the blanks against said stop member to align said flanges endwise and for clamping said flanges in aligned inter-fitting relation, and means for clinching together the flanges of the clamped blanks.

In testimony whereof I have signed my name to this specification.

JAMES A. GRAY.
